ABSTRACT: A student desk having a horizontal top, leg structures at each side of the top, and a book box offset toward one side of and below the top. The book box has a sidewall and lower wall inclined from horizontal in the same direction to support books in both a standup or laydown position. The book box is secured to the top and to the leg structure at one side of the desk, a modesty panel is secured to the book box and the leg structure at the other side of the desk, and the book box and panel strengthen the leg structures.

STUDENT DESK

This invention relates to a student desk of unique construction. More particularly, the invention relates to a student desk of extremely durable and rugged construction having a book box or compartment for standup or laydown storage of student's books.

Student desks known in the past have included a book box or compartment offset to one side of the desk top and suspended from the top to provide a knee space for the student at one side of the book box. The previously known desks, however, were inconvenient for the student to use because the book box was either too large or too small. Where the book box was made large enough to accommodate all the student's books including large size notebooks, the knee space adjacent the book box was inadequate for student comfort. On the other hand, where the book box was made small enough to provide for adequate knee space, the book box was of insufficient size to hold all the various sizes of books, including notebooks, which the student would customarily place in the book box.

An additional shortcoming of the prior art desks resides in that the prior book boxes do not maintain the books in a standup or upright position. With the prior art boxes, it is virtually impossible for the student to store only several books in an upright manner because the outside book of the group of books frequently fell over onto the bottom of the book box, absent some auxiliary device such as a book end to hold the books upright. Hence, the student was required to merely pile the books one upon the other on the lower shelf of the book box with the result that removing books from the book box was quite inconvenient.

An additional shortcoming of prior art school furniture or student desks is that the modesty panel required in such furniture is usually inadequately secured to the desk with the result that the construction lacked durability. Such nondurable construction is believed to result from securing the modesty panel along its top edge to the underside of the top and securing the sides of the modesty panel at only a few points to the remainder of the desk.

By virtue of the unique construction of the desk of this invention there is provided a rugged, durable and inexpensive student desk which overcomes the shortcomings of the prior art constructions. Among the features of this desk is a unique book box with a sloping sidewall and sloping bottom wall joined at a corner to the sidewall to provide for conveniently storing books in either a standup or laydown fashion so books can conveniently be placed in and removed from the book box. A related feature is that the inner sloping wall of the book box is adjacent the knee space of the desk and permits use of a book box wider at its top than the previously known book boxes for a desk of a particular size, without decreasing the usable knee space of the desk. In fact, that portion of the knee space which contributes most to the comfort of the student is actually increased so the student has more comfort leg room than with prior art desks having smaller book boxes.

The modesty panel of the desk of this invention is also unique in that the modesty panel has a sloping front, whereby it can be rigidly secured to the book box at one side and can also be rigidly secured to one of the legs of the desk at the other side. This construction is also accomplished without reducing the comfort knee space of the desk. As a result of the construction of the book box and modesty panel arrangement with the modesty panel secured to one of the rigid legs of the desk, the legs are braced by the book box and the modesty panel to provide a desk of extremely strong durable construction.

Correspondingly, an object of this invention is a unique student desk having a book box which provides for standup, as well as laydown storage of books and which provides substantial usable knee space for a desk of a particular size.

Another object is a student desk according to the aforementioned object wherein the additional knee space is provided by inclining the sidewall of the book box slightly from vertical and by inclining the lower wall of the book box slightly up-

wardly in the same direction, so books placed in the book box in a standup position against the sidewall will remain in this position without the need for book ends or other accessories to hold the books upright.

5 Another object is a student desk of rugged construction in which the inner sidewall of the student desk is sloped to provide a book box of substantial width adjacent its top, and which includes a notebook shelf spaced slightly from the top of the book box to accommodate books which it is not desired to store in the lower portion of the book box.

An additional object is a desk of rugged construction in which the book box and modesty panel cooperate with the legs of the desk to reinforce and brace the legs.

15 A still further object is a student desk having a top and a pair of inverted U-shaped leg assemblies at each side of the top and in which a book box and modesty panel cooperate with the legs and top to provide a durable desk construction wherein the legs are reinforced by the book box and modesty panel.

20 Numerous other features and advantages of the student desk of this invention will become apparent with reference to the drawings, which form a part of the specification, and in which:

25 FIG. 1 is a rear elevational view of the desk of this invention showing the desk as viewed from behind the position of a student sitting at the desk, and showing books positioned in a standup fashion in the desk book box;

FIG. 2 is a right-hand end view of the desk of FIG. 1;

30 FIG. 3 is a partial view, in section, taken along line 3—3 of FIG. 1 and showing the sloping modesty panel and the manner in which it is secured to one of the supporting legs for the desk;

FIG. 4 is a partial view, in section, taken along line 4—4 of FIG. 1;

35 FIG. 5 is a partial sectional view taken along line 5—5 of FIG. 1;

FIG. 6 is a fragmentary view, in section, taken along line 6—6 of FIG. 2; and

40 FIG. 7 is a fragmentary view, in section, taken along line 7—7 of FIG. 5.

FIG. 8 is a real elevational view similar to FIG. 1, but showing books positioned in stacked fashion. Referring now to the drawings in detail and particularly to FIGS. 1—3 there is shown a student desk 1, in accordance with this invention, having a flat top 2, inverted U-shaped leg structures 3 and 4 secured to and extending downwardly from opposite sides of the desk top, a modesty panel 5, and a book box 6. Leg structure 3 (FIG. 3) includes tubular legs 7 and 8 which diverge in a direction away from the desk top and which are integrally connected by a short horizontal tubular portion 9 parallel with and extending horizontally along the lower face of the top adjacent one side edge of the top. Leg structure 4 is similarly constructed and includes tubular legs 10 and 11 which diverge in a direction toward the floor and which are integrally connected by a tubular horizontal portion 12. Leg structure 4 extends along the underside of top 2 adjacent the other side edge of the top.

As shown at FIGS. 1 and 2, top 2 is generally rectangular and has parallel side edges 13 and 14, and parallel front and rear edges 15 and 16, respectively. Leg structure 4 is secured to top 2 by an elongated angle bracket 17 (FIG. 6). Angle bracket 17 has a horizontal top leg 18 and a vertical side leg 19. Horizontal leg 18 has a slight offset so the inner portion 20 of the leg is spaced slightly from the bottom surface 21 of top 2, for a purpose which will subsequently be described in detail. The horizontal portion 12 of leg structure 4 is secured to both legs 18 and 19 of the angle bracket by resistance welding and the leg structure is then secured to the top of the desk by screws 22 which pass through suitable openings in leg 18 and into the pressed particle board from which top 2 is formed. Leg structure 4 is so positioned that it lies in a plane perpendicular to the top and spaced slightly inwardly of and parallel with side edge 14. Leg structure 3 is secured to the top with its

tubular portion slightly inwardly of side edge 13 using an angle bracket 23 secured to the leg structure and the desk top in a manner identical to that described for leg structure 4.

As shown at FIG. 2, leg structure 4 includes an elongated strengthening brace 26 which extends between legs 10 and 11 at a location spaced from and parallel with tubular horizontal portion 12. Brace 26 is welded to the respective legs.

Leg structure 3 also has an elongated strengthening brace 27 which extends between legs 7 and 8 and is welded to the respective legs. As shown at FIG. 7, brace 26 is formed from a sheet steel channel of generally inverted U-shaped cross-sectional configuration and opens downwardly as at 28. The inwardly facing surface 29 of the sidewall of brace 26 extends inwardly of a plane tangent to the inside of leg structure 4 for a purpose which will subsequently be described in detail.

Book box 6 is formed from sheet steel and includes an upright sidewall 31 (FIG. 1) integral with a sloping lower wall 32 and a sloping second sidewall 33. Sidewall 31, lower wall 32, and sidewall 33 are formed from a single blank of sheet metal bent at corners 34 and 35 to the configuration shown in FIG. 1. As shown at FIGS. 1, 2, 4 and 5, the front edges 34 of wall 31-33 are continuous and coplanar and these edges are rolled outwardly, rearwardly, and then inwardly to provide a smooth cylindrical front edge completely free of sharp edges. Rear edges 35 of each of sidewall 31-33 lie in a common plane parallel with front edges 34, and the rear edges are rolled to provide a smooth continuous cylindrical edge at the rear of the book box.

The rear of book box 6 is closed by a rear wall 37 of an outline configuration such that its edges engage the inside surfaces of walls 31-33. The rear wall is formed with flanges 38, 39, and 40 (FIGS. 4 and 5) which extend at a right angle to the plane of the rear wall and engage respectively, the inside surfaces of walls 31, 32, and 33. The rear wall is secured to walls 31-33 by spot welding, as at 41 at spaced-apart intervals along the flanges, so the several flanges 38-40 are secured to these walls. As shown at FIGS. 4 and 5, the outside surface 42 of rear wall 37 is spaced slightly inwardly of rear edges 35.

Extending between the sidewalls 31 and 33 is a combined notebook shelf and pencil tray which takes the form of a flat horizontal intermediate wall 44. The intermediate wall has upwardly turned side flanges 45 and 46, which are bent parallel with the respective sidewalls 31 and 33 and engage and are spot welded to these sidewalls to secure the intermediate wall in position. Intermediate wall 44 also has a downwardly turned rear flange 47 which is slightly spaced from and parallel with rear wall 37. The front edge of intermediate wall 44 is rolled downwardly and rearwardly to form a smooth cylindrical bead 49 free of sharp edges. Immediately inwardly of the bead 49 is a shallow arcuate depression 40 which forms a pencil tray. Narrow reinforcing tabs 51 and 52 extend upwardly from opposite sides of depression 50 and are spot welded respectively, to sidewall 31 and sidewall 33 to reinforce the front portion of the intermediate wall and maintain it rigid. As shown at FIG. 4, the front edge bead 49 of the intermediate wall is spaced slightly inwardly of the front edge 34 of the book box.

Book box 6 is mounted below the upwardly facing writing surface 60 of top 2 of the desk. FIG. 1 shows the mounting of the book box 6 for a right-handed student. Sidewall 31 is parallel with and adjacent the inside of leg structure 4, and the upper ends of sidewalls 31 and 33 abut lower surface 21 of top 2. Sidewall 33 has an outwardly extending flange 61 (FIG. 4) at its top edge which lies flat against the bottom surface 21 of the top. The flange extends the length of the top edge of sidewall 33 and is provided with suitable openings to receive screws 62, whereby the flange is secured to the top.

Sidewall 31 similarly has an outwardly extending continuous flange 62 along its top edge to facilitate securing this side of the book box to top 2. With reference to FIG. 6, outside surface 68 of wall 31 engages leg 19 of angle 17 and, flange 63 extends between the upper surface of inner portion 20 of the leg 18 and the bottom surface 21 of the top, and is clamped between inner portion 20 of the angle and the top. In addition,

screws 64 (FIG. 5) may also be inserted through suitable openings adjacent the opposite ends of flange 63 to prevent the flange from slipping out of its clamped position between angle 17 and top 2.

Book box 6 is also secured to leg structure 4. As shown at FIG. 7, the outside surface 68 of sidewall 31 lies flat against the inwardly facing vertical surface 29 of brace 26. The surface 29 projects inwardly of legs 10 and 11 a distance equal to the thickness of leg 19 of angle 17 so wall 31 can be mounted substantially vertical. Wall 31 is secured to brace 26 with pop type rivets which are inserted through aligned openings formed in wall 31 and the wall 69 of race 26 and the rivets are then expanded in the usual manner by a suitable tool from inside book box 6. The advantage of using pop type rivets is that the outwardly facing exposed wall 70 of brace 26 does not have to be drilled or otherwise be performed to expand the rivets, and hence, presents a more pleasing appearance.

Modesty panel 5 is also formed from sheet metal. As shown at FIGS. 1 and 3, modesty panel 5 is generally trapezoidal, as viewed in plan, and extends between wall 33 of the book box and leg 8 of leg structure 3. The modesty panel has a smooth lower edge 70' formed by rolling the material at the edge of the panel to provide a smooth cylindrical reinforced lower edge.

Modesty panel 5 has a side flange 71 which is curved to conform to the cylindrical surface of the leg and extends generally at right angles to the face of the panel. The modesty panel is secured to leg 8 with pop rivets 72, which extend through flange 71 and into the leg. The pop rivets permit forming blind holes in leg 8 so the rivets are not visible from the other side of the leg. Flange 71 is elongated so its upper end can also be riveted to the upright leg of the angle 23 by passing a rivet 73 through a suitable opening and then deforming it. At the opposite side of modesty panel 5 is another side flange 74 (FIG. 4) which extends at right angles to the face of the panel and abuts the outside of sloping sidewall 33. As shown at FIGS. 3 and 4, the top of modesty panel 5 is tilted back away from front edge 15 so it follows the slope of leg 8, and the flange 74 is welded to sidewall 33 with the panel in this inclined position by spot welds 75.

With the desk assembled as shown at FIG. 1, top surface 76 of lower wall 32 extends at an angle of 15° to horizontal and forms a similar angle with the plane of writing surface 60, since the leg structures 3 and 4 support this writing surface in a generally horizontal plane. In addition, the sloping wall 33 extends at an angle of 75° with writing surface 60, and correspondingly makes the same angle with the horizontal. (The angle between sidewall 33 and vertical is 15°). This provides a sloping inside surface 77 which joins the inclined surface 76 at an angle of 90°. While the specified angles of 15° and 75°, respectively, for the inclination of lower wall 32 and sidewall 33 have been found to be of particular advantage, it has been found that angles in the range of 10° to 20° for the inclination of surface 76 and 70° to 80° for the slope of surface 77 are also satisfactory for standup or laydown positioning of books in the book box.

The advantage of sloping or inclining the walls 32 and 33 is to permit books 78 to lean against surface 77 while in the upright position of FIG. 1 without any tendency for the books to fall over toward leg structure 4 as the books would do if walls 32 and 33 were horizontal and vertical, respectively. In addition, there is no tendency at all for the lower edge of the books 78 to slide toward leg structure 4 because of the inclination of lower wall 32.

If desired, books 79 may be placed in the book box in stacked fashion, as shown at FIG. 8, so the sides of the books are parallel with wall 32. When stacked as shown at FIG. 8, the books 79 will have one of their end edges resting against surface 77 of sidewall 33.

An additional advantage of the slope or inclination of sidewall 33 is that book box 6 has substantial width at intermediate wall 44, so that books of substantial height or width, such as the notebook 80 can be placed on the intermediate

wall without interference with sides 33 or 31 in the region above the wall.

An additional advantage attained by sloping sidewall 33 is that additional knee space is obtained in the region between the sidewall 33 and leg structure 3. For purposes of explanation, this additional knee space shall be termed knee comfort space because when a student sits at the desk with his knees extending into the knee space, the top of the knee or thigh of the student is usually 3-4 inches from lower surface 21 of top 10 2. Hence, the tops of the student's knees or thighs, designated 81 and shown in phantom lines at FIG. 1, are approximately even with the top surface of intermediate wall 44. By virtue of the sloping side 33, additional space is therefore provided in which the student can move his knees and feet and against which he can comfortably lean one of his legs, if desired.

While modesty panel 5 slopes slightly away from the front edge 15 of the desk top, this slight slope does not detract from the knee comfort space beneath the desk because a student rarely sits with the chair seat pulled under the desk so his knees can contact the inside surface of the modesty panel.

While the book box and modesty panel of the desk 1 are described as formed from sheet metal, other materials, such as rugged plastic, fiber board, or wood can also be used, whereupon appropriate fabrication techniques will be used to assemble the desk.

While the lower ends of legs 7, 8, 10 and 11 are shown as integral with the respective leg structures and taper inwardly toward the glides 82 which engage the floor, conventional adjustable lower legs can be used to permit adjusting the height of the desk for use by students of various age groups.

In view of the foregoing explanation, it will be apparent that the desk of this invention includes a top 2 with an upwardly facing writing surface 60, horizontally supported by leg structures 3 and 4 at opposite sides of the top. The book box 6 is supported beneath the top adjacent leg structure 4 and is secured to both the top and the leg structure 4 in this "offset position", at one side of the desk. Front edges 34 and rear edges 35 of the book box lie within and are parallel with vertical planes passing through the front edge 15 and rear edge 16 of the desk top, and modesty panel 5 extends between and is secured to book box 6 and leg structure 3.

What is claimed is:

1. A student desk comprising, in combination

a desk structure comprising

a top having an upwardly facing writing surface, and
leg means supporting the top with the writing surface in a
generally horizontal position;

a book box below said writing surface and comprising

a first transversely extending generally upright sidewall,
a second transversely extending sidewall spaced from said
first sidewall and presenting a first inside surface facing
upwardly and toward said first sidewall, and

a lower wall extending between said first and second
sidewalls and having a second inside surface facing up-
wardly and away from said first sidewall; and

means securing said book box to said desk structure.

2. A student desk according to claim 1 wherein
said first and second surfaces extend at an angle of approxi-
mately 90° to each other.

3. A student desk according to claim 1 wherein
said book box further includes

a generally upright rear wall extending between cor-
responding side edges of said first and second walls and
said lower wall.

4. A student desk according to claim 1 wherein
said leg means includes

a first pair of legs at one side of the top, and
a second pair of legs at the other side of the top; and

said book box is secured to said desk structure with said first
sidewall adjacent said first pair of legs and said second
sidewall spaced from said second pair of legs to provide a
knee space between said second sidewall and said second
pair of legs.

5. A student desk according to claim 1 wherein

said first surface has a slope in the range of 10° to 20° from
vertical; and

said second surface has a slope in the range of 10° to 20°
from horizontal.

6. A student desk according to claim 5 wherein
the slope of said first surface from vertical is 15°; and
the slope of said second surface from horizontal is 15°.

7. A student desk comprising, in combination
a desk structure comprising

a generally rectangular top having spaced-apart front and
rear edges, spaced apart side edges, and an upwardly
facing writing surface, and

leg means supporting the top with the writing surface in a
generally horizontal position;

said leg means including

a first leg structure including a pair of legs adjacent one
side edge of the top, and

a second leg structure including a pair of legs adjacent the
other side edge of the top;

a book box below said writing surface and comprising

a first generally upright sidewall,

a second sidewall spaced from said first sidewall and
presenting a first inside surface facing upwardly and
toward said first wall, and

a lower wall extending between said first and second
sidewalls and having a second inside surface facing up-
wardly and away from said first sidewall;

means securing said book box to said desk structure with
said first sidewall adjacent and secured to said first leg
structure and said second sidewall spaced from said
second leg structure to provide a knee space between said
second sidewall and said second leg structure and with
corresponding side edges of said first and second
sidewalls and said lower wall in a plane generally parallel
with said front edge of the top; and

a generally upright modesty panel extending across said
knee space adjacent said front edge of said top;
said modesty panel being secured to said second leg struc-
ture and to said book box;

whereby, said box and modesty panel cooperate to rein-
force said leg structure against bending.

8. A student desk comprising, in combination

a desk structure comprising

a top having an upwardly facing writing surface, and
leg means supporting the top with the writing surface in a
generally horizontal position;

a book box below said writing surface and comprising

a first generally upright sidewall,

a second sidewall spaced from said first sidewall and
presenting a first inside surface facing upwardly and
toward said first sidewall, and

a lower wall extending between said first and second
sidewalls and having a second inside surface facing up-
wardly and away from said first sidewall;

means securing said book box to said desk structure; and
wherein,

said book box further includes

an intermediate wall extending horizontally between said
first and second sidewalls and between said top and
said lower wall.

9. A student desk comprising, in combination a

desk structure comprising

a top having an upwardly facing writing surface, and
means supporting the top with the writing surface in a
generally horizontal position;

book compartment means below said top for receiving
books in a standup, inclined slightly from horizontal position,
and in a laydown, inclined slightly from vertical position,
said book compartment means comprising

a first sidewall of thin sheet metal extending at an acute
angle to said writing surface and presenting a first up-
wardly facing book supporting surface inclined slightly
from vertical, and

a lower wall of thin sheet metal extending at an acute angle to said writing surface and presenting a second upwardly facing book supporting surface inclined slightly from horizontal, said lower wall being integral with said first sidewall and extending therefrom at an angle of approximately 90°, 5
 a generally upright second sidewall of thin sheet metal integral with said lower wall and in spaced relation to said first sidewall, and
 a generally upright rear wall welded to corresponding side edges of said side and lower walls; and
 an intermediate wall extending horizontally between and secured to said first and second sidewalls, said intermediate wall being in spaced relation to said lower wall. 10
 10. A student desk comprising, in combination
 a desk structure comprising
 an elevated top having an upwardly facing writing surface bounded by horizontally extending front and rear edges and a pair of spaced-apart side edges extending transversely between said front and rear edges; and
 means supporting the top with the writing surface in a generally horizontal position; 15
 book support means beneath said writing surface and opening in a direction toward the rear edge of said writing surface, said book support means comprising
 said wall means extending transversely of said top and presenting a first upwardly facing book support surface extending at an acute angle to said writing surface and generally parallel to the side edges of the writing sur- 20
 25
 30

face;
 bottom wall means extending transversely of said top and presenting a second upwardly facing book support surface at an acute angle to said writing surface and generally parallel to the side edges of the writing surface, said sidewall means and bottom wall means forming a generally L shaped structure facing toward said top; and
 means securing said book support means to said desk structure with said book support means offset toward one of the side edges of the writing surface. 11. A student desk according to claim 10 wherein said first and second book support surfaces extend at an angle of 90° relation to each other. 12. A student desk according to claim 11 wherein said first book support surface extends at an angle of approximately 75° relative to said writing surface. 13. A student desk according to claim 10 wherein said book support means further includes generally vertical second sidewall means spaced from said first mentioned sidewall means and extending between said bottom wall means and said top. 14. A student desk according to claim 13 wherein said book support means further includes generally vertical rear wall means extending between common end edges of said first and second sidewall means and bottom wall means, and offset toward the front edge of the writing surface. 35
